UNITED STATES PATENT OFFICE.

JOHN W. MCCOY, OF SINKS GROVE, WEST VIRGINIA.

DESIGN FOR A HATCHET.

SPECIFICATION forming part of Design No. 35,154, dated October 1, 1901.

Application filed June 8, 1901. Serial No. 63,814. Term of patent 7 years.

To all whom it may concern:

Be it known that I, JOHN W. MCCOY, a citizen of the United States, residing at Sinks Grove, in the county of Monroe and State of West Virginia, have invented a new and original Design for a Hatchet, of which the following is a specification, reference being had to the accompanying drawings, in which—

Figure 1 is a perspective view of a hatchet, showing the novel design. Fig. 2 is an edge view of the same, looking toward the recessed side of the head. Fig. 3 is an end view of the same, taken from the pointed end of the handle.

The leading or material feature of the design consists of the head 10 and extension 11 thereof, which head and extension project on opposite sides of one end of the handle 12, while the extension 11 is located farther from the butt of the handle than the head 10. The main body of the head is considerably thicker than the extension 11 thereof and is provided in that edge which lies farthest from the handle 12 with a square or rectangular recess 13, located about centrally of the length of the head 10, so as to leave broad flat surfaces 14 and 15 at opposite sides of the recess 13, the said flat surfaces 14 and 15 being substantially square or rectangular. The extension 11 terminates in a sharp edge 16, which extends substantially parallel with the plane of the handle 12, and the side edges of the ex-

tension 11 are inclined and diverge from the plane of the handle toward the edge 16. The outer edge 17 of the extension inclines from the outer edge 18 of the head to a considerable distance beyond the plane of the head and meets the edge 16 at an acute angle. The inner edge 19 of the extension 11 forms an acute angle with the edge 16 and also with the handle 12, reaching from said edge to the handle and meeting the handle about in line with the inner portion of the recess 13. The edge 19 of the extension 11 is also formed with a V-shaped notch 20. The extremity of the handle 12 is beveled on opposite sides and brought to a thin edge 21. The surfaces 14 and 15 form a hammer. The recess 13 constitutes a wrench. The extension 11 provides a hatchet-blade. The notch 20 is for the purpose of extracting nails and other fasteners, and the tapered extremity 21 of the handle constitutes a screw-driver.

Having thus described my invention, what I claim as new, and desire to secure by Letters Patent, is—

The design for a hatchet as herein shown and described.

In testimony whereof I affix my signature in presence of two witnesses.

JOHN W. MCCOY.
